(57) CLAIM

The ornamental design for an infrared sauna for isometric exercise, as shown and described.

DESCRIPTION

FIG. 1 is an isometric view of an infrared sauna for isometric exercise;

FIG. 2 is another isometric view thereof;

FIG. 3 is a cross sectional view taken from the top thereof;

FIG. 4 is a cross sectional view showing a floor thereof;

FIG. 5 is a cross sectional view showing a first side wall thereof;

FIG. 6 is a cross sectional view showing a back wall thereof;

FIG. 7 is a cross sectional view showing a second side wall thereof; and,

FIG. 8 is a cross sectional view showing a front wall thereof. The broken lines illustrate portions of the infrared sauna for isometric exercise training that form no part of the claimed design.
